CONVEYER MECHANISM

Orin Kelly, Columbus, Ohio

Application February 4, 1935, Serial No. 4,926

8 Claims. (Cl. 198—220)

My invention relates generally to novel conveyor mechanisms for conveying loose material such as for example, and more particularly, lump coal, either to merely convey the material from one location to another or to screen it in such conveying movement, the invention being useful, by way of examples, in constructions in which the material is to be conveyed along a substantially horizontal path or along a path of slight 5 inclination, as for example in coal loaders, loading and screening machines, loading boom machines, conveyers and screeners, either of the travelling type or the stationary type.

Certain of my objects are to provide a novel, 15 simple and inexpensive construction of conveyor mechanism for loose material provided either as a screening means or a mere conveyor chute; to provide in an apparatus embodying a plurality of such mechanisms, for the so balancing of the 20 shocks produced in the operation of the apparatus as to practically eliminate vibrations; to provide such a mechanism of a type of construction whereby it may by slight change be rendered 25 suitable for performing different kinds of work and useful in different types of apparatus; to provide transfer apparatus for comparatively fragile, loose, material, such as for example coal, whereby the breakage of the loose material commonly incident to the use of transfer apparatus 30 as hitherto used will be greatly reduced; and other objects as will be manifest from the following description.

Referring to the accompanying drawings:

Figure 1 is a view in side elevation of a coal 35 screening apparatus having a substantially horizontal screen-conveyor section, and constituting one embodiment of my invention.

Figure 2 is an enlarged plan view, taken at the line 2 on Fig. 1 and viewed in the direction 40 of the arrow, of the end of the apparatus of Fig. 1 at which the mechanism for actuating the conveyor elements of the apparatus, is located.

Figure 3 is a plan view of the apparatus of Fig. 1.

Figure 4 is an enlarged sectional view taken 45 at the line 4 on Fig. 2 and viewed in the direction of the arrow.

Figure 5 is an enlarged sectional view of the 50 drive mechanism shown in Fig. 4, with a portion thereof removed to disclose interior details.

Figure 6 is a section taken at the line 6 on Fig. 5 and viewed in the direction of the arrow.

Figure 7 is an enlarged view in longitudinal 55 sectional elevation of the left-hand end of the apparatus shown in Figs. 1 and 3, the section be-

ing taken at the line 7 on Fig. 3 and viewed in the direction of the arrow.

Figure 8 is a similar view of the other end of the apparatus, likewise taken at the line 7 on Fig. 3 and viewed in the direction of the arrow, Fig. 8 being a continuation of Fig. 7 and with the latter showing the entire apparatus in longitudinal sectional elevation.

Figure 9 is a view in side elevation of a small loading boom apparatus, preferably designed to 10 rescreen the material from a storage bin and to load trucks therewith, the same constituting another embodiment of my invention.

Figure 10 is an enlarged fragmentary sectional view of a detail of the mechanism of Fig. 9, the 15 section being taken at the line 10 on Fig. 9 and viewed in the direction of the arrow; and

Figure 11, a view in longitudinal sectional elevation of a coaling boom apparatus constituting still another embodiment of my invention and of 20 a type having a section at the receiving end of the apparatus confined to move horizontally and along which the loose material is carried, and a swinging section for the delivery end and along 25 which the material is conducted, the section being taken immediately inside of one of the opposite side portions of the frame.

Referring to the construction shown in Figs. 1 to 8, inclusive, the structure comprises a framework 12 carrying a hopper 13 having a reciprocable trough-shaped bottom 14, a chute section 15 through which the loose material, as for example coal, to be transferred, and in this particular instance, re-screened, flows to the hopper 13, a screen conveyor chute 16 and a screenings collector and conveyor trough 17 located below, and in vertical alignment with, the screen portion of the conveyor chute 16 and comprising the perforated bottom 18 of this chute, the trough 17 having a terminal trough section 19 hinged thereto at its discharge end as represented at 20.

The bottom 14 of the hopper 13, the screen conveyor chute 16 and the screenings collector and conveyor 17 all of which are shown as horizontally disposed, except for the slight downward tilting of the conveyor trough section 19, are provided with surfaces, shown as presented by wear-resisting horizontal plates 21, 22, and 23, at which these reciprocable elements are supported on wheels 24, 25, and 26, respectively, 45 journalled on the framework 12.

The mechanism shown for reciprocating the elements 14, 16, and 17 comprises a main drive shaft 27 journalled on the framework 12 and having sprocket chain connection 28 with a jack 50

shaft 29 journalled on the framework and carrying an eccentric device 30, the strap portion 31 of which is pivotally connected at 32 with one end of the hopper bottom 14, by a link 33.

As will be understood from the foregoing, the material supplied to the hopper 13 through the chute 15 is fed from the former to the screen conveyer 16 by reciprocating the hopper bottom 14 through the medium of the mechanism above described, the movement of the hopper bottom 14 to the right in Figs. 1-3 and 7 serving to advance the loose material in the hopper and the resistance afforded by the material in the chute 15 to retrograde movement of the material advanced in the chute 13, insuring the dropping of the fed material from the discharge end of the hopper bottom 14 upon the movement of the latter to the left in Fig. 7.

The mechanism for actuating the conveyer sections 16 and 17 is of such construction as hereinafter described that the speed of travel thereof during the latter part of their forward or feed strokes and the first part of their backward or return strokes is accelerated to such degree that the inertia of the material on the conveyer sections, upon the initial return movements of such sections, is not overcome thereby resulting in the movement of the conveyer sections rearwardly relative to the material thereon and producing feed of the material by the conveyer sections.

The conveyer-actuating mechanisms referred to and both of the same construction and provided for actuating the conveyer troughs 16 and 17, are represented at 34 and 35 and each comprises a broad faced eccentric 36 rigidly keyed at 37 to the drive shaft 27 and provided around its central part with a ring spur gear 38, either cast integral with the eccentric 36 or made separatare therefrom and rigidly attached thereto.

Surrounding the eccentric 36 is an eccentric yoke 39 shown as split in two crosswise in the usual manner as represented at 40, with the front half of the yoke split lengthwise as indicated at 41, to facilitate assembly of the parts of the yoke.

Bronze bushings represented at 42 and secured to the eccentric yoke or strap 39 to be non-rotatable relative thereto are interposed between the eccentric 36 and this yoke at opposite sides of the gear 38 and are provided to take the wear of the relatively moving parts. Wear is compensated for by placing shims between the two halves of the bushings rather than by the usual method of placing shims between the two halves of the eccentric yoke which would disturb the pitch lines of the gears.

Provision is made for running the ring gear 38 and the eccentric 36 in lubricant by hollowing out the yoke 39 around the ring gear as represented at 43 and providing oil-retainer plates 44 at opposite sides of the eccentric yoke at its lower end, to form a receptacle for oil or grease.

Each eccentric mechanism 34 and 35 also comprises a spur pinion 45 meshing with the gear 38 and rigidly secured to a shaft 46 journalled in the front end of the yoke 39, the shaft 46 being provided at its ends with eccentrically disposed pins 47 forming cranks to which actuating or connecting rods 48 and 49 are connected, one pair of these rods being pivotally connected with one end of the screen conveyer chute 16, as represented of one of these rods at 50, and the other pair pivotally connected with one end of the trough conveyer 17, as represented of one of these

rods at 51. The ratio of ring gear 38 and pinion 45 is as 2 to 1; hence the cranks 47 make two rotations to one of the eccentric 36.

Cast on the lower part of each eccentric yoke 39 is a lug 52 to which one end of a guide bar 53 is rigidly riveted as represented at 54, the bar 53 having a portion 55 which extends alongside of, and between, the pair of connecting rods 48 and 49 with which it is associated, and contains a horizontally elongated guide slot 56 into which a pin 57 secured to these rods and carrying a rotatable sleeve 58 extends. The bars 53, one provided for each pair of connecting rods 48 and 49, as shown, thus serve to maintain these rods in alinement with the centers of the eccentrics 36, which otherwise would "break" around the cranks 47.

As will be noted, rotation of the eccentrics 36 rotates the spur gears 38 connected therewith and also drives the eccentric yokes 39, and the gears 38 actuate the pinions 45 meshing therewith, thereby rotating the cranks 47. Thus the lengthwise movement of the rods 48 and 49, and consequently the conveyer elements 16 and 17, is produced by the action of the eccentrics 36 as modified by the cranks 47 which rotate at a speed different from that of the eccentrics, in the construction shown at such speed as to cause them to make two complete revolutions while the eccentrics are making one revolution. This movement of the rods 48 and 49 is such in the construction shown as to cause the conveyer elements 16 and 17 to move during the latter part of the feed stroke and the first part of the return stroke at a speed greater than during the remaining portions of these strokes, thereby permitting the inertia of the moving material as moved on the feed stroke, to effect a feeding action of the loose material on the conveyers.

Referring particularly to the actuation of the conveyer screen element 16 and assuming that this element is at the beginning of its feed stroke (effected by movement of the element to the right in the drawings) in which position the eccentric drive mechanism 34 therefor would be in the position shown in Figs. 4-6, clockwise rotation of the eccentric 36 in Figs. 4 and 5 throughout the first quadrant, namely, to the position shown in Fig. 7, causes the cranks 47, through the gear connections 38 and 45, to rotate 180° from the position shown in these figures. The eccentric 36, which is operated at uniform speed, thus shifts the yoke 39 and rods 48 and 49 associated therewith to the right in the drawings, but as the cranks 47 in this movement move from their extreme right-hand position (Figs. 4-6) to extreme left-hand position, namely, through 180°, the rods 48 and 49 are advanced a distance equal only to the throw of the eccentric 36 less the throw of the cranks 47. Thus assuming the eccentric to have an 8 inch throw and the cranks a 1½ inch throw, the rods 48 and 49 will be moved 2½ inches in this first quadrant movement of the eccentric 36 and at relatively low speed.

The rotation of the eccentric 36 clockwise through the second quadrant causes the cranks 47 to rotate 180° back to the position shown in Figs. 4-6 and as these cranks in these operations rotate in the direction of movement of the eccentric 36, the rods 48 and 49 will be moved a distance equal to one-half the throw of the eccentric plus the throw of the cranks, namely, in the particular example given 5½ inches to the end of their feed stroke and thus at a greatly ac-

celerated speed compared with the speed of movement of these rods during the first part of the feed stroke.

In the movement of the eccentric 36 through the third quadrant the cranks 47 move from the position shown in Figs. 4-6 throughout 180° and thus the rods 48 and 49 are moved to the left in the drawings at accelerated speed, in the particular example given throughout 5½ inches; and in the rotation of the eccentric through the fourth quadrant, in which movement the cranks 47 move 180° to the position shown in Figs. 4-6, the rods 48 and 49 are moved at a much reduced speed, moving, in the particular example given, 2½ inches. By providing the mechanism as described the connection between the eccentric 36 and the conveyer element to be operated is of non-constant length, variable under the action of the mechanism to produce acceleration of the speed of movement of the conveyer during such portions of the cycle of reciprocatory movement thereof as to permit the inertia of the moving material to effect a conveying action, it being noted that a relatively high speed of approach to, and recession from, the end of the forward or feed stroke, which causes the material being conveyed to move forward by the momentum built up therein, and a relatively low speed of approach to the beginning of the feed stroke and throughout the beginning of the feed stroke, thereby preventing any backward movement of the loose material, is effected; these several speed changes being effected progressively and smoothly.

The operation of the conveyer element 17 by the eccentric mechanism 35, to deliver the fine particles discharged through the screen 18 to the chute 17, corresponds with the actuation of the conveyer element 16 as above described, except that the conveyer movement of the element 17 is to the left in the drawings (instead of to the right as in the case of the conveyer element 16), the material discharging onto the conveyer section 19 and thence discharging from the left-hand end of the inclined end thereof; the eccentric mechanism 35 to this end involving the setting of the cranks 47 thereof at 180° from the position shown in Figs. 4-6 in the position therein shown of the eccentric 36 relative to the drive shaft 27, which will cause the conveyer element 17 to move throughout the latter part of its feed stroke to the left in the drawings and the fore part of its return stroke, at accelerated speed, as compared with the first part of the feed stroke and the last part of the return stroke.

Referring to the construction shown in Figs. 9 and 10, it comprises a storage bin 54, shown as permanently fixed, provided to receive the loose material to be transferred, as for example 60 coal, and having a discharge outlet portion 55 provided with a sloping bottom 56.

Below the bin 54 is a containing frame 57 of structural steel surmounted by a bracket frame 58 on which a vertically swingable and reciprocable chute 59, shown as having a screen bottom portion 60, and located beneath the outlet of the bin 54, is supported at wheels, one of which is shown at 61 journaled to the screen chute 59 at opposite sides thereof, the wheels 61 being supported on runways on the frame 58, one only of which is shown at 62. The outer end of the chute 59 is engaged by any suitable means for raising and lowering it into the desired inclined position, a portion of a means for this purpose being represented at 63.

Provision is made for reciprocating the chute section 59 in accordance with the general principle of operation above described in connection with the conveyer sections 16 and 17 modified, however, to regulate the propulsion force given to the loose material thereon as the inclination of the swinging chute is increased or diminished.

In this arrangement the chute 59 is provided with rearwardly extending bars 64 at opposite sides thereof provided at their extremities with heads 65 in which the journal ends 66 of a swivel block 67 are journaled, the block 67 having an opening therethrough at which it is slideable up and down on a lever 68 fulcrumed on a shaft 69 journaled in the bracket frame 58.

The lever 68 is rocked, to effect the desired feed action of the conveyer chute 59, by eccentric mechanism represented generally at 70 and of the same general construction, and operating in the same way, as the eccentric mechanisms 34 and 35, the drive shaft for this mechanism being represented at 71, the eccentric thereon at 72, the eccentric yoke at 73, and one of the pairs of cranks, operated from the eccentric 72 through the gears (not shown), at 74, these cranks being connected, respectively, with a pair of rods 75 which are pivoted at 76 to a depending lug 77 on the sliding swivel block 67. The bars 75 are shown as guided by a modification of the guide means of the preceding figures and comprising a bar 78 rigidly secured to the yoke 73 and extending along the bars 75 and connected with the latter, between the cranks 74 and the swivel block 67, by a link 79 pivoted to the bars 75 and 78.

Since chute 59 is free to move in either direction except for its attachment to the lever 68 through the block 67, any change of inclination of the chute will automatically adjust the swivel block to the lever 68.

As will be understood from the foregoing the greater the inclination of the chute 59 the more the amplitude or amount of travel is reduced.

Thus the mechanism is rendered automatically regulable to avoid travel or flow of the material in the chute 59 greater than that required for any degree of tilt thereof, to the end of avoiding breakage of the loose material.

Where the work required to be performed demands heavier equipment than that shown in Figs. 9 and 10 and a conveyer section at the receiving end confined to horizontal movement, in addition to a swinging conveyer section at the delivery end, is required, as is usual where a large tonnage is loaded in railroad cars, a construction of the form shown in Fig. 11 is preferred.

This construction comprises a reciprocable trough conveyer 80 resting at wear plates 81 on wheels 82 journaled in the sides of a frame 83 and adapted to receive the loose material to be transferred supplied thereto as from a bin such as shown at 54, 55 in Fig. 9.

Below the trough 80 and positioned to receive the discharge therefrom is a conveyer chute 84 shown as pivotally connected at the rear of its bottom, as represented at 85, to the lower ends of hanger bars at opposite sides thereof, one being represented at 86, these bars being pivotally supported at their upper ends at opposite sides 70 of, and laterally beyond, the chute section 84, on a cross bar 87 carried by the frame 83, whereby the chute 84 may not only rock on its pivot 85 but may also move bodily lengthwise along the machine by swinging on the pivot 87.

The trough 80 and the chute 84 are actuated to effect the feeding of the material therealong to the right in the drawings in accordance with the principle of operation of the conveyer sections 16, 17, and 59 (the propulsion effect produced by the actuation of the chute 84 being automatically regulable in accordance with the degree of tilt to which the operator sets this chute as in the case of the chute 59 of Figs. 9 and 10).

To this end the trough 80 and chute 84 are associated with geared eccentric mechanism 88 and 89, respectively, of the same construction as the mechanism 35 and driven from a main drive shaft 90.

The bar portion of the eccentric mechanism 88 and corresponding with the bar portion 48, 49 of the mechanism 35, is represented at 91 and is pivotally connected with the trough member 80 as represented at 92.

The eccentric drive for the chute section 84 comprises in the particular construction shown two of the eccentric mechanisms 89 located at opposite sides of the eccentric mechanism 88, and the bar portions of which (one only thereof being shown at 93 and corresponding with the bar portion 48, 49 of the mechanism 35) are pivotally connected, as represented of one of the bar portions 95 and 94, to the lower ends of rock levers 95. The levers 95 are located at opposite sides of, and laterally beyond, the trough 80 and are pivotally supported at their upper ends on a cross bar 96 carried by the frame 83. Slidable along the curved portions of the bars 95 are swivel blocks, one only of which is shown at 97, having pivots, one of which is represented at 98, to which rearwardly extending spaced apart arms 99 on the chute 84 and located at opposite sides of, and laterally beyond, the trough 80, are pivotally connected. Said arms 90 as shown may be integral extensions of the side members of said trough 84 and are disposed in the rear of that end of the bottom of the trough 84 terminating adjacent the pivot 85.

The rock levers 95 are preferably of the flat bar type and curved as shown which is desirable in this relatively heavy equipment as the curving of the levers permits the force to be applied along the radii of the curves.

The guide means for the bars 91 and 93 are of the same type as those shown in Figs. 9 and 10 and comprise rigid bars 100 and 101 and links 102 and 103 connecting these bars, respectively, with the bars 91 and 93.

If desired one only of the eccentric mechanisms 89 may be provided, in which case it would be desirable to provide the bar portion 93 as a single bar having a fork at which it would connect with the levers 95.

As will be understood, the bottom of either, or both, of the members 80 and 84 may be perforated or provided of screen form, as illustrated at 100 of a part of the bottom of the chute 84, where rescreening of the loose material is desired.

As will be understood from the foregoing, a machine constructed in accordance with my invention is not only simple of construction but may be built at low cost.

Furthermore, the structure lends itself, particularly where a plurality of conveyer elements are provided as in the case of certain of the illustrated machines, to the balancing of the shocks of the conveyer elements and thus minimizing vibration.

By changing the throw of the cranks to which the connecting rods are connected, the feed action of the material may be altered to adapt the machine for different work.

While I have illustrated and described certain particular constructions embodying my invention I do not wish to be understood as intending to limit it thereto as the construction shown may be variously modified and altered and the invention embodied in other forms of structure without departing from the spirit of my invention, and as an example of additional forms in which the invention may be embodied, and wherein two conveyer elements, as for example screen elements, are employed, particularly where these elements are of light weight, these elements may be driven by a single one of the eccentric mechanisms, such as the mechanism 35 and the balancing of one of the elements against the other effected by setting the cranks of the eccentric mechanism (the cranks 47 of the mechanism shown) at 180 degrees apart and connecting one of the screen-conveying elements referred to to each of the cranks.

What I claim as new, and desire to secure by Letters Patent, is:

1. Conveyer mechanism comprising a reciprocable element for supporting material to be conveyed, and mechanism for reciprocating said element comprising a drive member having an eccentric, a driven means operated thereby, connecting means between said driven means and said element for controlling operation of the latter comprising a rotary member on said driven means geared to said eccentric, and an eccentric connection between said element and said rotary member.

2. Conveyer mechanism comprising a reciprocable element for supporting material to be conveyed, and mechanism for reciprocating said element comprising a drive member having an eccentric, a driven means operated thereby, connecting means between said driven means and said element comprising a rotary member on said driven means geared to said eccentric and operating to drive said rotary member at a differential speed relative to said drive means, and an eccentric connection between said element and said rotary member.

3. Conveyer mechanism comprising a reciprocable element for supporting material to be conveyed, and mechanism for reciprocating said element comprising a drive member having an eccentric, a strap member about and driven by said eccentric, gear teeth on said eccentric, connecting means for said element, a rotary member on said strap member having gear teeth meshing with the teeth on the eccentric and operative to drive said rotary member at a greater speed than said eccentric, and a crank connection between the connecting means and said rotary member.

4. In combination, a conveyer element supported for to and fro movement lengthwise thereof and adapted to be adjusted into different angular positions, and means for imparting such to and fro movement to said element as to effect the propulsion of material to be conveyed comprising a rock member, a drive member, a reciprocable member actuated by said drive member, a rotary member on said reciprocable member driven by said drive member, a second reciprocable member eccentrically connected with said rotary member and connected with said

5 rock member for rocking the latter and a member 5
slidable on said rock member toward and away from its pivot and operatively connected with said element and automatically adjustable along said rock member in the movement of said element into different angular positions.

5. In combination, a conveyer element supported for to and fro movement lengthwise thereof and adapted to be adjusted into different angular positions, and means for imparting such to and fro movement to said element as to effect the propulsion of material to be conveyed comprising a rock member, a drive member including an eccentric, a reciprocable member driven by said eccentric, a gear on said eccentric, a rotary member on said reciprocable member and driven by said gear, a second reciprocable member eccentrically connected with said rotary member and connected with said rock member for rocking the latter and a member slidable on said rock member toward and away from its pivot and operatively connected with said element and automatically adjustable along said rock member in the movement of said element into 25 different angular positions.

6. In combination, a drive member including an eccentric, an element reciprocated by said eccentric, a gear on said eccentric, a rotary member on said element driven by said gear and a second reciprocable element eccentrically connected with said rotary member, 5

7. In combination, a drive member, a strap member, means to drive the strap member eccentrically from the drive member, a rotary member journalled on the strap member in driving relation to the drive member, a reciprocating member and an eccentric driving connection between the rotary member and reciprocating member, 10

8. In combination, a drive member, a strap member, means to drive the strap member eccentrically from the drive member, a rotary member journalled on the strap member in driving relation to the drive member, a reciprocating member, an eccentric driving connection between 20 the rotary member and reciprocating member, a guide arm extending from the strap member, and a sliding connection between the guide arm and reciprocating member.

ORIN KELLY. 25
